RECIPROCATIVE ELECTROMAGNETIC TOOL

Hobart D. Andreae, Maynard R. Andreae, and
Wayne A. Andreae, Birmingham, Mich.

Application September 17, 1947, Serial No. 774,488

6 Claims. (Cl. 143—73)

1

This invention relates to reciprocative electromagnetic tools, and particularly electromagnetic jig saws. The invention may be considered an improvement on the disclosure of the Young Patent 1,948,229 issued February 20, 1934.

An object of the invention is to adapt a tool-driving armature to flex to and from an electromagnet and to provide for bodily adjusting such magnet to and from the armature to regulate the air gap of the magnetic field.

Another object is to associate a tool-driving armature with an electromagnet, to interpose a resilient spacer means between the magnet and a support therefor, and to secure the magnet to the support by a connection applying a regulable stress to the spacer means.

Another object is to interpose a corrugated sheet metal spring between an electromagnet and a support therefor, and to clamp the magnet to the support by an element extending through and imposing compression on the spring.

Another object is to support an electromagnet upon and within an open-topped housing, to provide said housing with a cover serving also as a work table, to dispose a flexible armature beneath said cover, for vibratory actuation by the magnet, and to operatively position the armature by securing its ends between the cover and housing.

Another object is to mount the ends of a vibratory flexible armature in cushions of rubber or the like set into holders suited to be rigidly clamped in their positions of use.

Another object is to equip the gooseneck of a jig saw with a guide for the saw blade, adjustable to and from the work table to engage the blade in a desired close proximity to the work.

These and various other objects are attained by the construction hereinafter described and illustrated in the accompanying drawings, wherein:

Fig. 1 is a side elevational view of our invention as incorporated in an electromagnetic jig saw.

Fig. 2 is a front view of the same.

Fig. 3 is a longitudinal sectional elevation taken on the line 3—3 of Fig. 2.

Fig. 4 is a vertical cross sectional view taken on the line 4—4 of Fig. 1.

Fig. 5 is a horizontal cross section taken on the line 5—5 of Fig. 4.

Fig. 6 is a perspective view of a spring employed to seat the electromagnet on a support.

Fig. 7 is a perspective view of one of a pair of cushioning mountings for the armature extremities.

2

Fig. 8 is a perspective view of a hanger adapted to be carried by the gooseneck and to accurately position the saw blade.

Fig. 9 is a longitudinal vertical sectional view of a modification of the construction illustrated in Figs. 1—8.

Fig. 10 is a horizontal sectional view of the modification, taken on the line 10—10 of Fig. 9.

In these views, the reference character 1 designates an approximately rectangular housing, open at top and bottom and formed preferably as a casting. Centrally disposed in said housing is an electromagnet comprising a coil 2 wound on the center pole piece 3 of a laminated E-shaped core 4. Said pole piece and the lateral pole pieces 5 and 6 project upwardly from the yoke portion of the core and terminate in pole faces 7 preferably slightly below the top edge of the housing 1. A support for the described electromagnet is formed by a channel-shaped strut 8 integrally bridged between opposed walls of the housing, the core having a stud 9 welded centrally to its bottom face and extending downwardly through the strut 8 to receive a nut 10 upwardly seating against the strut. Between the magnet and strut is interposed a corrugated sheet metal spring 11, substantially equal in width to the core, such spring seating at its extremities 11a and mid portion 11b on the strut, and having crests 11c between its mid portion and ends to seat the core. The stud 9 extends through a central aperture 12 in said spring, and upon tightening the nut 10, the spring is selectively compressed. It is evident from preceding description that the spring ends are free to recede from its anchored center portion as compression is applied, the crests 11c sliding on the bottom face of the core 4 and the extremities 11a sliding on the strut, any rotation of either the spring or magnet being prevented by the marginal upstanding flanges 13 of the strut.

Surmounting and covering the housing 1 is a work table 14 having a reinforcing marginal skirt 15 and an annular downwardly projecting flange 16 inwardly spaced from said skirt and adapted to register with and form an upward continuation of the housing 1.

The work table is detachably secured on the housing by a pair of stud bolts 17 freely upwardly inserted in perforated bosses 18 formed on opposite ends of and adjacent the top edge of the housing. The top portions of said end walls and said bosses thereon are outwardly offset, as indicated at 19, rendering the bolts 17 readily accessible. Said studs are threaded into posts 18 of the

table formed interiorly integral with opposite ends of the flange 16.

Coextensive in height with the housing 1 are two similar pairs of ribs 19a, the ribs of the respective pairs inwardly projecting from the respective end walls of the housing and being equally laterally spaced from the bolts 17. Two similar pairs of ribs 20 on the table, coextensive in height with the flange 16, project inwardly from the ends of such flange. Clamped between the upper and lower jaws formed by the ribs 20 and 19 are elongated metallic receivers 21 having lugs 22 at their ends to engage said jaws. Within said receivers are fitted cushions 23 of rubber or like resilient material, medially formed with pockets snugly receiving the ends of a resilient flexible armature 24 of sheet steel or other magnetically active material. The mid portion of said armature is disposed above the electromagnet for periodic attraction to the pole faces 1. When the coil 2 is energized by an alternating current, the rapid periodic changes in value of such current produce a vibration of the armature, its mid portion alternately being attracted to and springing away from the magnet. Mounting of the armature by inserting its ends in cushions of yielding material, as above described, affords a very essential freedom of movement to said ends, allowing them to tilt and also to move slightly to and from each other, under flexure. It is to be noted that the bolts 17 are at opposite ends of and in the medial longitudinal plane of the armature, being thus adapted to draw the upper clamping jaws firmly down upon the end lugs of the receivers 21 to firmly clamp the latter against the lower jaws.

Centrally secured to the armature is an arched bracket 25 serving as an anchorage for the lower end of a saw blade 26, extending freely upward through a central aperture 27 in the table 14. The upper end of said blade is anchored to the free end of a spring arm 28 fixed at its other end on the gooseneck 29. The latter is of the usual U-shape, its lower end being fastened by screws 30 to and beneath the table 14 and its upper end portion being spaced above the table. The top arm of the gooseneck projects slightly beyond the blade-mounting end of the spring arm 28 and has a downturned end 31 to which is clamped, by a bolt 32 and wingnut 32a, a downwardly projecting hanger 33, longitudinally slotted at 34 to permit its up-and-down adjustment on the bolt. The upper portion of said hanger is received in an opening 35 of the gooseneck, to resist any tendency to turn about the bolt 32. The lower portion of the hanger 33 extends rearwardly at a downward inclination across the path of reciprocation of the blade, then downwardly to mount a screw 36, rearwardly of the blade, and terminates in a foot 37 forwardly projecting across the path of the blade and notched to accommodate the blade. The rearwardly inclined portion of the hanger is slotted at 38 to accommodate the blade, and the screw 36 has its head diametrically grooved to receive and guide the blade.

For most efficient cutting, with a minimum breakage of blades, it is desirable to guide the blade in close proximity to the work, resisting both side thrust and undue rearward thrust applied by work to the blade. The slotted head of the screw 36 is suited to resist both types of thrust and the vertical adjustability of the hanger permits its lower end to be maintained in close proximity to work, despite variations in thickness of the latter.

As compared to earlier types of electromagnetic jig saws, the described construction lends itself to a much quicker and easier assembly. The tightening of a single nut 10 on the bolt 9, serves to properly position the electromagnet and no flexing of the armature or any supports for same is necessary to insert the armature ends in their cushioning mountings. Employment of only two bolts to secure the work table to the housing saves further time, as does also the use of these fastenings to hold the armature in operative position. The most efficient operating relation between the armature and magnet may be readily established since the nut 10 may be adjusted while the machine is being test-operated.

It is to be noted that the hanger 33 adds materially to safety of the described tool, in addition to performing the functions heretofore mentioned. Thus said hanger extends in front of the major portion of such length of the blade as is exposed above the work, preventing the hand of an operator from being thrust against such portion. While the lower portion of the hanger 25 is disposed rearwardly of the blade, a shielding function is also derived from such portion by reason of its foot 37 projecting forwardly beyond the toothed edge of the blade.

In the modification illustrated by Figs. 9 and 10, the housing 39, table 40, electromagnet coil 41 and electromagnet core 42 substantially conform to preceding description. Also as in first-described construction, the ends of the armature 43 are inserted in cushions 44 set into elongated receivers 45 clamped between jaws 46 on the housing and jaws 47 of the table, such jaws engaging the ends of the receivers. It is preferred, in this modification, however to secure the table to the housing and impose a clamping stress on said jaws by bolts 48 disposed adjacent to and between the cushioned ends of the armature, the latter being formed with apertures 49 at its medial longitudinal axis freely accommodating said bolts. The bolts have their lower ends inserted in bearings 50 and are headed to seat on said bearings. The latter are supported by arms 51 and 52 extending respectively from the end and side walls of the housing. Bosses 53 downwardly projecting from the table are tapped to receive the bolts. As compared to the first-described construction this modification achieves an increased strength through reducing the spaced relation between the two bolts.

What we claim is:

1. In a reciprocative tool, the combination with a work table having an aperture to accommodate a reciprocative work-performing element and having a portion forward of said aperture for feeding work to said element, of a gooseneck having one end secured to said table and its other end spaced above the table, a resilient flexible arm mounted upon and beneath the upper end portion of the gooseneck for anchoring the work-performing element, a guide arm for said element downwardly projecting from said end portion of the gooseneck forwardly of the path of reciprocation of said element and vertically adjustable on the gooseneck and having a portion between its ends rearwardly offset across said path of the work-performing element and apertured to accommodate such element, and having its lower end formed with a work-engaging foot forwardly projecting across said path and apertured to accommodate said element and means for clamp-

ing said guide arm to the gooseneck in selectively spaced relations to the table.

2. In a reciprocative tool as set forth in claim 1, a headed screw fixed in the guide arm, and having its head grooved to receive and guide said element.

3. In a reciprocative tool, the combination with a work table having an aperture to accommodate a work-performing element and having a portion forward of said aperture for feeding work to said element, and means for reciprocating such element transversely to the table, of a support spaced above the table, and a guide arm for said element mounted on and depending from the support, forwardly of the path of said element, 15 said arm having a work-engaging foot at its lower end and having a portion, spaced above such foot, offset rearwardly across said path.

4. A reciprocative tool as set forth in claim 3, said foot projecting forwardly across the path of said element.

5. In combination with an electromagnet and a coacting vibratory armature formed of sheet material, of a pair of units for operatively mounting the ends of the armature, each such unit comprising an elongated cushion formed with a socket to receive the corresponding end, and a substantially rigid receiver for said cushion, having lugs extending from the cushion ends for receiving clamping pressure, whereby said cushion 30 affords an angular play of the armature end, a mounting for said electromagnet and units, and means for applying clamping pressure to said lugs.

6. A reciprocative electromagnetic tool comprising an open-topped housing, a work table covering the housing, an electromagnet carried by and within the housing, a resilient vibratory ar-

mature extending above and flexible to and from said magnet and having its ends interposed between the housing and work table, resilient cushions engaging and mounting the ends of the armature, metal receivers socketed to retain said cushions, a work-performing element attached to and driven by the armature, and means for securing the work table to the housing, effective through said table to clamp said receivers upon and within the housing.
